CLAIM

The ornamental design for a telephone, substantially as shown and described.

DESCRIPTION

FIG. 1 is a top plan view of a telephone showing my new design;

FIG. 2 is a front elevational view;

FIG. 3 is a side view;

FIG. 4 is a rear view; and

FIG. 5 is a perspective view taken from the front and to one side, and showing the door open, and the telephone handset removed from its hook.

FIG. 1

FIG. 2

FIG. 3

FIG. 4

FIG. 5
